HAT MANUFACTURE AND THE
PRODUCTS THEREOF

Joseph M. Mayleas, New York, N. Y.

Application February 25, 1935, Serial No. 7,959

2 Claims. (Cl. 2—178)

This invention relates to hat manufacture, and the products thereof.

Although, in particularly describing the invention herein, reference will be made specifically to the manufacture of straw hats, and especially those types worn by women, in which the hat is made from woven thin straw, yet, in certain of its aspects, it will be found that the invention may have application to the manufacture of hats from other materials.

After the blank, produced by weaving the straw-braid or otherwise developing the raw materials for the hat, has been molded to a desired shape, and the form has been trimmed by the operator to define the desired contouring of the brim, there is left a sharp raw edge of undesirable effect. Resort has previously been had to complicated processing to convert this raw edge into a rounded edge of neat appearance for the hat. However, generally there was left, beneath the brim, an undesirable protrusion which, in some cases, had the same cutting properties as the original raw edge.

It is an object of the invention to overcome these deficiencies. By a process in accordance with the invention, hats of the character here set forth are finished easily and simply, and at greatly reduced expense, resulting in a finished product of desirably neat and fine appearance. By such a process, a finishing member is applied to the hat brim in such manner as simultaneously to result in ironing down the hat brim edge to leave a rounded finished contouring for the brim, without any cutting or raw edge formation.

It is an object of the invention to provide, as an article of manufacture, a hat of the type described in which, without stitching or similar operations, there is produced a finished edge of neat appearance, all at a cost favorably related to present-day manufacturing cost.

Other objects of this invention will herein-after be set forth, or will be apparent from the description and the drawing, in which are illustrated certain features by which the invention may be effectuated.

The invention, however, is not intended to be restricted to any particular construction or arrangement, or to any particular application thereof, or to any specific method of manufacture or manner of use, or to any of various details herein shown and described, as the same may be modified in various particulars or be applied in many varied relations without departing from the spirit and scope of the claimed

invention, the features herein illustrated and described being merely to demonstrate the invention.

On the drawing, in which the same reference characters refer to the same parts throughout, and in which are disclosed such features above referred to:

Fig. 1 is a perspective view of a hat brim, comprising features in accordance with the invention;

Fig. 2 is an elevational view, illustrating a method of applying protective edging, in accordance with the invention, to the hat brim;

Fig. 3 is an elevational view, illustrating another method of applying the protective edging; and

Fig. 4 is a vertical, transverse cross-sectional view, on the line 4—4 of Fig. 1.

While there is here used for illustrative purposes, in connection with the description of the invention, a straw hat 10, it is to be understood that, in certain particular aspects, hats made from other materials, as, for instance, felt, may be the subject of certain of the operations to be described. Hat 10, shown in Fig. 1, includes a hat brim 12 extending from body 14. Edge 16 of brim 12 is shown as folded over and turned under the brim, providing a section 18 disposed beneath body 14. Bridging between and covering over section 18 and the portions of the underface 20 of body 14 immediately contiguous to the section is a strip 22.

By suitable means, this strip may be caused to adhere to both section 18 and body 14. For instance, between the strip and the straw of the hat may be a material which assumes adhesive properties, to retain the strip adhering to both section and body, when the hat brim is ironed down. In a specific form of the strip as used herein, a fabric 24, for instance, a ribbed material, prior to application to the hat material, has had a surface 26 thereof coated with a suitable adhesive material 28. In the particular case here described, a material such as gutta percha is used for this purpose, being applied to the fabric in any well-known manner to remain adhering to the fabric without penetrating therethrough, and so that, as finally processed in accordance with this invention, it will not have penetrated through the strip itself, but will remain disposed at that face 50 in immediate proximity to the hat body and section 18.

To produce a hat with a brim 12, such as here described, the edge of the brim may be molded by hand or otherwise, so that section 18 will be 55

disposed beneath the body, as shown in Fig. 4. To complete this operation, the rough formation must be ironed down so as finally to dispose it in proper relationship to the body of the hat. However, prior to ironing the edge down against the body, a strip 22, of the character just described, is disposed to bridge between section 18 and the body at face 20. Then, while the brim is supported on a proper mold, pressure may be brought 10 to bear, with a hot iron 30, as, for instance, against face 32 of the brim body. Heat will be transmitted through the brim body to the strip, thus causing the applied substance 28 to assume its adhesive properties, and to effect adherence 15 between the strip and the parts against which it is contacted.

If desired, the iron may be directly pressed against the strip itself. In one relation, at least, efficient operation and a more effective result has 20 been derived from pressing the iron against face 32. In such relation, an effective result was had from the use of a damp cloth 34, as shown in Fig. 2, disposed over face 32 during the ironing operation, in which case the iron travelled over 25 this dampened cloth.

An even more effective and efficient operation was consummated by the use of a so-called steam iron, that is, an iron 36, as shown in Fig. 3, having openings 38 through its base, by means of which 30 live steam, conducted to the iron, may be discharged as desired against the surface over which the iron is then passing, thus providing a degree of moisture which, in cooperation with the heat of the iron, results in a proper working of the 35 hat material. For such operation, it was found more advisable that surface 32 rest upon the mold, and that the iron bear directly against section 18, face 20, and strip 22.

The moisture, in either case, in conjunction with 40 a strip 22, especially one having a gutta percha coating, effects a result of unexpected importance. First of all, the fabric of strip 22 is left without any sheen or similar distracting effect. However,

of more importance is the fact that the adherence of the strip to section 18 and body 14 becomes markedly effective under such circumstances. At the same time, and by this same operation, the bent-under section 18 and the hat body are positively ironed to the desired shaping and finish, the covering-over strip 22 being fixed in position, eliminating any of the sharp undesirable effects of free edge 16.

Many other changes could be effected in the 10 particular methods of operation, and the products thereof, set forth, and in specific details thereof, without substantially departing from the invention intended to be defined in the claims, the specific description herein merely complying 15 with the requirements of a disclosure of the elements necessary for a comprehension of the spirit of the invention.

What is claimed as new and useful is:—

1. In the art of hat manufacture wherein, from 20 a crude blank, there has been formed a hat brim, the method of converting the raw edge of the brim to a smoothly finished edge, which comprises the steps of bending the raw edge of the brim beneath the brim, thereafter applying 25 to the bent raw edge of the brim a strip which assumes adhesive properties upon being subjected to heat, and subjecting the strip and the brim to the action of a hot iron simultaneously to form the brim edge and to cause the strip to ad- 30 here to and cover over the raw brim edge.

2. An article of manufacture comprising a brim for a hat, the brim having a free raw edge, the raw edge being turned under the brim, and a strip located and covering over the raw 35 edge of the brim, the strip having in contact with the raw edge an adhesive facing made effective by heat, the strip and the turned-down raw edge being ironed down against the hat brim body so that the strip covers over and retains, and 40 provides the only means for retaining, the raw edge flat against the body of the brim.

JOSEPH M. MAYLEAS.
